(57) **CLAIM**

The ornamental design for a scalloped edge plate, as shown and described.

DESCRIPTION

FIG. 1 is a front, perspective view of a scalloped edge plate showing our new design;

FIG. 2 is a front view thereof;

FIG. 3 is a rear view thereof;

FIG. 4 is a right side view thereof, the left side view being a mirror image of the right side view;

FIG. 5 is a top view thereof; and,

FIG. 6 is a bottom view thereof.

The broken lines in the drawings are included for the purpose of illustration and form no part of the claimed design.

1 Claim, 4 Drawing Sheets
